UNITED STATES PATENT OFFICE

HENRY McHALEY, OF LONG BEACH, CALIFORNIA, ASSIGNOR, BY DIRECT AND MESNE ASSIGNMENTS, OF ONE-HALF TO GEORGE G. CUNNINGHAM AND ONE-HALF TO VINCENT R. CUNNINGHAM, BOTH OF LOS ANGELES, CALIFORNIA

FISH TAIL BIT

Application filed August 31, 1927. Serial No. 216,582.

My invention relates to the art of deep well drilling being more particularly a form of bit for use in drilling wells by the rotary method of drilling. Bits of the character referred to usually weigh from three hundred to five hundred pounds, are costly, and require frequent sharpening to keep the same in proper condition for performing their function in advancing the hole. It follows that when the sharpening operation is necessary, the entire bit must be removed from the drilling string by breaking the joint at the head of the bit, which joint is ordinarily the hardest joint in the string to break.

15 The principal object of my invention is to provide a removable blade for bits of the fish-tail type, of simple form and construction, which may be readily removed from the bit proper.

20 By providing such a removable blade, of a weight of fifteen or twenty pounds, it is immediately apparent that by having on hand a number of such blades that the change from a dull bit to a sharp one may be quickly made with considerably less effort than in cases where the whole bit must be removed. It is to be noted also, that the blades may be made of material considerably harder than the body of the bit, at less expense than where the entire bit is hardened or consists of consequently more expensive material.

25 Other objects and advantages will appear hereinafter, from the following description and drawings.

30 Referring to the drawings which are for illustrative purposes only,

Fig. 1 is a face view, in elevation, of a bit, embodying a form of my invention.

35 Fig. 2 is a side elevation of the bit shown in Fig. 1.

Fig. 3 is a perspective view of the blade shown on the bit in the preceding figures.

40 Fig. 4 is a sectional plan view on line 4—4 of Fig. 1, and

45 Fig. 5 is a modified form of construction, illustrating a simplified form of my invention.

More particularly describing the embodiment of my invention shown in the drawings,

50 10 designates a head having a tapered thread-

ed pin 11 thereon for attachment to the drilling string in the usual manner.

12 designates the bit body which extends downwardly from the head in the form of a flat member, consisting of two legs 13, joined centrally by a web 14. These legs 13 are slightly offset with relation to each other, as shown in Figs. 2 and 4, diverging downward and outwardly from a common plane directly under the head 10.

The legs 13 are recessed at their lower portion on opposite faces as indicated at 16, the upper end of such recesses forming shoulders 17 undercut to engage a correspondingly shaped rib 18, formed on the upper end of a blade 20 which, in general, may be of any suitable form. These shoulders take the up-thrust on the blade and being undercut firmly, hold the blade against outward twist at its upper end.

The blade 20 extends transversely of the bit and between the legs 13, fitting in the recesses 16 formed in the legs, the lower end of the legs 13 being behind the portion of the blade engaged thereby when rotated as 75 in the direction of the arrow in Fig. 4.

The blade 20 is secured to the legs 13 by means of headed bolts 22, held in place by a cotter pin 22'. It is to be noted that a longitudinal channel 23 is formed on each side 80 of the bit body which receives a stream of flush water from ducts 24, indicated in dotted lines in Figs. 1 and 2, and that the blade 20 is provided on opposite sides with a lug or projection 25, engaged by the inner edge of a 85 cooperating leg 13 which takes the side thrust of the blade. The lugs 25 are tapered on one face as indicated at 26, for directing wash fluid from the corresponding channel 23 toward the exposed face of the blade.

90 For the purpose of more firmly holding the blade in fixed relation to the legs 13, I may provide the blade with ribs 18', the upper face of which is angularly disposed to engage the angular lower face 13' of the legs 13.

95 For the purpose of mixing the mud formed by the cuttings from the bit mixed with the fluid heretofore referred to, I may provide holes 27 formed in the body and notches in 100

the edges or sides of the body as shown at 28.

In the form shown in Fig. 5, the legs 13 are of the same construction as shown in the preceding figures, except the shoulder 17 is not undercut.

5 What I claim is:

A fish tail bit comprising: a body, a head on said body having fluid passages therethrough, legs on said body terminating in spaced offset parallel relation, a web interposed between and connecting said legs to form oppositely disposed channels communicating with said fluid passages in the head, a blade secured to said legs, and lugs on said blade for directing fluid from said channels to the opposite faces of said blade.

In testimony whereof, I have hereunto set my hand at Los Angeles, California, this 6th day of August, 1927.

HENRY McHALEY.
